US0D1106234S

(12) **United States Design Patent** (10) **Patent No.:** **US D1,106,234 S**
Mongrain et al. (45) **Date of Patent:** **** Dec. 16, 2025**

(54) **DISPLAY SCREEN OR PORTION THEREOF WITH GRAPHICAL USER INTERFACE**

(71) Applicant: **Google LLC**, Mountain View, CA (US)

(72) Inventors: **Scott Allen Mongrain**, Seattle, WA (US); **Amy Lynn Sims**, San Mateo, CA (US); **Antoine Sevilla**, San Francisco, CA (US); **David Christopher Everly**, Arvada, CO (US); **Takafumi Iwai**, Tokyo (JP); **Kate Schutzenge**, Brooklyn, NY (US)

(73) Assignee: **GOOGLE LLC**, Mountain View, CA (US)

(**) Term: **15 Years**

(21) Appl. No.: **29/913,308**

(22) Filed: **Sep. 29, 2023**

(51) **LOC (15) Cl.** **14-04**

(52) **U.S. Cl.**

USPC **D14/485**

(58) **Field of Classification Search**

USPC **D14/485-495**

See application file for complete search history.

(57) **CLAIM**

The ornamental design for a display screen or portion thereof with graphical user interface, as shown and described.

DESCRIPTION

The sole FIGURE is a front view of a display screen or portion thereof with graphical user interface showing the new design.

The outermost dashed broken lines show an electronic device, which is environmental structure and forms no part of the claimed design. The dot-dash broken lines show a display screen or portion thereof and form no part of the claimed design. The remaining broken lines showing text and portions of the graphical user interface form no part of the claimed design.

1 Claim, 1 Drawing Sheet
